UNITED STATES PATENT OFFICE.

OLAF B. JACOBSEN, OF BIRMINGHAM, ENGLAND.

EXTRUSION-PRESS.

1,400,071.

Specification of Letters Patent. Patented Dec. 13, 1921.

Application filed September 12, 1918. Serial No. 253,773.

To all whom it may concern:

Be it known that I, OLAF BERG JACOBSEN, a subject of the Kingdom of Great Britain, residing at "Glenthorne," Valentine Road, 5 King's Heath, Birmingham, in the county of Warwick, England, engineer, have invented certain new and useful Improvements in Extrusion-Presses, of which the following is a specification.

10 This invention relates to an extrusion press such as is used for the manufacture of tubes and hollow sections of the type involving a rod, to the extremity of which a mandrel is secured, said mandrel being of diameter 15 less than that of the rod, in which the said rod is located axially within a hollow plunger adapted to be advanced to effect the extrusion process, and in which the said rod is withdrawable independently of the plunger. 20 Previously, in this type of press, the rod has extruded in a backward direction through the main ram and pressure cylinder to an auxiliary pressure cylinder. According to the present invention, in this type of press 25 I utilize in lieu of the said rod, a plunger which is secured to the main ram and is adapted to exert a proportion of the extrusion pressure. The said hollow plunger is in this invention also adapted to be operated 30 by the main ram.

In order that this invention may be clearly understood and readily carried into practice, reference may be had to the appended explanatory drawing, on which:—

35 Figure 1 is a part elevation of an extrusion press according to the present invention.

Fig. 2 is a part sectional elevation of the extrusion press shown in Fig. 1.

40 Fig. 3 is a plan, partly in section, of the same.

In a convenient embodiment of the present invention, and referring to the drawings, *a* is the container from which the metal is adapted to be extruded; *b* is the die 45 through which the metal is extruded, and which is retained in position in relation to the container by any suitable provision. *b*¹ is a centralizing nipple for the front extremity of the mandrel *c*, which nipple is dislodged by the extruded tube. In the embodiment shown, rams *a*¹ located one on each side of the machine (and of which one is shown in Fig. 1) are adapted to operate rods *a*² which are connected to a sliding part 50 *p* in which the container *a* is mounted, and by which the latter is adapted to be retained

in effective engagement with the die *b*, which latter is supported by a holder *i*. A transverse slide *n*¹ is located in the opening *j*, said slide *n*¹ having a perforation through 60 which the extruded tube may pass. Said slide is adapted to be moved into and out of position by any suitable means, such as a double acting ram. This slide when in position functions as a resistance between 65 which and the container the die and its holder are securely clamped or gripped during the extrusion process. Rams for releasing the container from the die are indicated at *k*. The mandrel *c* is secured to a thrust 70 member *d*, which latter is in turn secured to the main ram *e*. *f* is a sleeve encircling the thrust member *d*, said sleeve being secured to a cross-head *g* adapted to be displaced forwardly by the main ram, and which is 75 coupled to auxiliary rams, the cylinders *h* of which are located above and below the cylinder of the main ram.

From the drawing, it will be seen that the thrust member *d* and sleeve *f* together 80 constitute the two parts of a composite extrusion plunger, *n* being the usual pad incorporated between the plunger and the metal to be extruded, and *o* being a ring which may be located between the pad *n* and the sleeve *f*. 85 The sleeve *f* is slidable on the thrust member *d*, and is of such form that its front face is in the plane of the front face of the thrust member *f* during the extrusion movement. The mandrel projecting from the front face 90 of the thrust member *d* being of a smaller diameter than said member *d*, occupies only a small part of the cross-sectional area of the container and both the inner and outer parts *d*, *f* of the plunger are adapted to move 95 through a distance equal substantially to the whole length of the container chamber.

At the end of the machine remote from the die an axially located stripping ram *p*¹ is adapted to move in its power stroke in 100 a direction away from the die and carries a cross-head *g* to which rods *l* are coupled; these rods *l* are coupled at their other extremities to bosses *m* upon the main ram and serve to effect the reverse movement of the 105 latter.

In operation the main ram *e* and auxiliary rams in the cylinders *h* move forwardly together and collectively displace the cross-head *g*, as a result of which the thrust member *d*, mandrel *c*, and sleeve *f* are collectively 110 displaced to extrude the metal without any

relative movement occurring between these parts. When the tube has been extruded the cylinders of the main ram *e* and the cylinders *h* are relieved of pressure. The container *a* 5 is then displaced a small distance away from the die *b*. The slide *n*¹ in the channel *j* is then displaced to permit of the removal of the die. Pressure is then again admitted to the cylinders *h* in order that the rams 10 therein may force the cross-head *g* and sleeve *f* forwardly independently of the main ram. As a result of this action the unextruded portion of the tube is expelled from the container. At about the same time pressure is 15 admitted to the cylinder of the stripping ram, which latter through the medium of the rods *l* is adapted to displace the main ram rearwardly to its initial position, as a result of which the tube is stripped from 20 the mandrel *c*. Pressure is then admitted to the cylinders *h* in the manner necessary to effect a rearward movement of the cross-head *g*, as a result of which the sleeve *f* is restored to its initial position. To permit 25 of this the rams in the cylinders *h* are double-acting.

What I claim as my invention and desire to secure by Letters Patent is:—

1. An extrusion press, involving a plunger, 30 to the extremity of which a mandrel is secured, said mandrel being of diameter less than that of the plunger, in which the said plunger is located axially within a hollow plunger, and in which the plunger first mentioned is adapted to exert a proportion of 35 the extrusion pressure.

2. An extrusion press as claimed in the

first claim, and in which the plunger first mentioned and also the said hollow plunger, are adapted to be operated by the main ram. 40

3. An extrusion press as claimed in the first claim, and in which a relative movement is permissible between the plunger first mentioned and the hollow plunger adapted to provide for the stripping of the work from the mandrel. 45

4. In an extrusion press, a container for the metal to be extruded, a die to close one end of the container, means to hold the die, a nipple arranged in the die and adapted to be dislodged therefrom by the extruded metal, means to release the container from the die, a cross head, guides therefor, means to operate the cross head, a thrust member, a ram to impart extruding movement to the thrust member and corresponding movement to the cross head, a sleeve carried by the cross head and arranged around and slidable on the thrust member and coacting therewith to form an extrusion plunger which is 60 adapted to enter the container, means independent of said ram to operate the cross head and sleeve, a pad on the outer end of the thrust member and arranged to enter the container, and a mandrel attached to the thrust member and extending through the pad, the container and the die, and also extending into an opening in the nipple. 65

In witness whereof I have hereunto set my hand in the presence of two witnesses. 70

O. B. JACOBSEN.
